MERCANDISE DISPLAY CASE

Clarence Earl Brooks, Morristown, Pa., and
Michael Mordkin, Columbia, N. J.

Application January 5, 1956, Serial No. 557,468

6 Claims. (Cl. 312—122)

This invention relates to cases for displaying merchandise for sale and particularly to devices for displaying merchandise that is kept in drawers or trays.

In order to have merchandise which is normally kept in drawers on display where it is in view of the customers, the drawers must be made of transparent material and this has increasingly become the practice, especially for the display of haberdashery, lingerie and other wearing apparel which it is desired to protect from dust. Various transparent plastic materials such as styrene are suitable for the purpose.

It is an object of this invention to provide a multiple drawer unit for this purpose which will fully exhibit the merchandise and which will be simple and inexpensive, which will make the merchandise easily and readily accessible and will be sufficiently sealed against dust and dirt for all practicable purposes. Other objects are pleasing appearance and strength and durability of construction. Other objects will be apparent from the detailed description which follows:

One of the advantages of the invention is the fact that it dispenses with separate lids for the individual drawers. In accordance with the invention the drawers mutually guide and seal each other. The frame member as contemplated has two relatively narrow uprights which permit the drawers to be exposed substantially at each end, and ribs on the drawers engage in grooves in the uprights to guide the drawers as they are moved in and out. The drawers are so constructed that they fit tightly together when closed and special guiding features of the drawers serve to effect the sealed condition. Each drawer except the uppermost interengages with the drawer above in overlapping relation along the sides, and the ends abut so as to make a tight closure and at the same time allow of the relative movement of the drawers. The top cross member of the frame has a fit with the top drawer so as to form a top guide for the top drawer and make a sealing closure for the top drawer when the drawer is closed. Preferably this guiding fit is effected by a plastic strip on the underside of the cross piece of a length and positioned to cover the drawer when closed and of a width to fit between the side walls and function as a guide.

To provide mutual lateral guiding between the drawers, each drawer has on its underside a pair of longitudinal runners or rails which are spaced so as to fit within the top edges of the side walls of the drawer immediately below. This overlap of the top edges of the side walls and the runners provides an effective seal between the drawers along their sides which is their major dimension. The end walls, both front and rear are set down below the side walls by the height of the runners, and the rear and front wall are notched at their two lower corners so as to admit and fit over and ride upon the projecting top edges of the side walls. Thus the drawers mutually support and guide each other and interfit so that they are effectively sealed to the exclusion of dust.

To assure easy movement and avoid scratching of the side walls by the frame uprights the drawers are pref-

2

erably proportioned and hung so as to clear the uprights. Specifically the drawer side walls may converge downwardly to a slight degree so as to assure such clearance below the side ribs.

5 Other features of the invention will appear from the following description of the embodiment of the invention illustrated in the accompanying drawings to which reference is now made.

Fig. 1 is an isometric view of a three drawer device 10 with the middle drawer partially open;

Fig. 2 is a transverse sectional elevation on the plane of line 2—2 of Fig. 1;

Fig. 3 is a longitudinal sectional elevation on the plane of line 3—3 of Fig. 1;

15 Fig. 4 is an isometric view of one of the drawers; Fig. 5 is a rear elevation of the device, partially in section; and

Fig. 6 is an enlarged fragmentary sectional elevation illustrating the downward convergence of the side walls 20 of the drawers and their clearance of the frame uprights.

The three drawers are duplicates and the frame is so devised that the drawers may be interchanged. The drawers are numbered 1, 2 and 3, beginning with the top drawer, and the same reference numerals will be given 25 to the corresponding parts of all three drawers. The drawers in their entirety are made of a suitable transparent plastic such as styrene and are illustrated as though of an integral molded construction, although in practice the component walls and other elements may be cut 30 from sheet material and cemented together in well-known manner.

The frame 4 is of any suitable material such as wood. It is a four sided open quadrangular structure having two uprights 5 and 6 forming side pieces which are spanned 35 by top piece 7 and bottom piece 8. As shown the bottom piece is wider from front to rear than the top and side pieces and is flush with the upright side pieces at its rear end but extends forwardly of the front edges of the uprights.

40 The uprights 5 and 6 are provided with three equally spaced longitudinal guide grooves on their inner faces, those in upright 5 being numbered 9, 10 and 11 and those in upright 6 being numbered 12, 13 and 14. These 45 grooves are open at their front ends and are closed at their rear ends, as shown, particularly in Fig. 3, the rear termini of all of the grooves being in substantially the same vertical plane.

The drawers are generally of conventional shape, having 50 their greatest or longitudinal dimension from front to rear. Each drawer is composed of side walls 15 and 16 which are substantially longer than the front-to-rear dimension of the uprights 5 and 6, and front and rear walls 17 and 18 and bottom wall 19. The width of the 55 drawers is substantially such as to occupy the space between the uprights, being slightly less so as to slide without frictional contact with the uprights.

On the under side of each bottom wall 19 are two longitudinal sealing strips 20 and 21, serving also as runners or rails, which extend the full length of the bottom 60 and are located inward from the outer face of the side walls by substantially the thickness of the side wall. The front and rear walls are offset downwardly with respect to the side walls by substantially the height of the runners 20 and 21 and the lower corners of each of the front and 65 rear walls are notched as at 22 to provide a rectangular clearance for the upward projection of the respective side walls of the drawer immediately below, the notches extending inwardly to the adjacent runners and upwardly to the plane of the lower face of the bottom wall 19. 70 Thus it will be seen that the bottom edge of the side walls of the upper drawers may rest upon the top edge of the corresponding side walls immediately below and

slide thereon, and that the side walls of the lower drawers fit over the runners of the drawer above and bear against the outer faces of the runners.

Supplemental means are provided for vertically spacing and longitudinally guiding the drawers. These means comprise longitudinal ribs 23 on side walls 15 and ribs 24 on side walls 16, the ribs being in the same horizontal plane and of equal length and width. The ribs extend from the front wall and terminate somewhat short of the rear wall. They are disposed with their upper faces in the plane of the top edges of the respective front and rear end walls and ribs 23 run in grooves 12, 13 and 14, respectively, and ribs 24 run in grooves 9, 10 and 11, respectively. The grooves are so located that they support the drawers with the side edges of the upper drawers at least approximately resting and sliding upon the side edges of the drawers immediately below. The bottom drawer rests with its runners actually upon or in close proximity to the top face of the bottom frame piece 8. Thus the forward projection of that bottom piece provides a support for the drawers supplementing the support by the ribs 23 and 24.

The width of the ribs is such that they bottom in the grooves and guide the drawers without any substantial lateral play. The width of the drawers is such that they will not rub against the uprights and be scratched, preferably being entirely free of the uprights, and, as shown in Fig. 6, the side walls are made slightly downwardly convergent by perhaps a degree departure from a right angle at the juncture of the side wall and bottom, thus accentuating the clearance. Not only does this prevent marring the side walls but it contributes to the free running of the drawers.

For appearance sake as well as utility, the front wall 17 of each drawer extends laterally on each end beyond the side walls to the plane of the outer edges of the ribs 23 and 24. Thus the front ends of the ribs are protected.

A cowl-like strip 25 across the top edge of each front wall is provided to be grasped by the fingers in pulling the drawer out.

Secured underneath the top piece 7 of the frame is a closure strip 26 of plastic and proportioned laterally to fit within the upper edges of the side walls of the top drawer and longitudinally to cover the drawer when the drawer is closed. Its thickness is equal to the downward offset of the end walls.

The ribs 23 and 24 are proportioned in length to abut with their rear ends against the closed ends of their slots when the drawers project substantially equally in front and rear of the uprights 5 and 6. That is the closed condition of the drawers and in that condition the bottom drawer has its front end flush with the front end of bottom piece 8 and the front walls 17 are all in the same vertical plane as are the rear walls 18. In that position the strip 26 serves as a cover for the top drawer, the top drawer covers the middle drawer and the middle drawer covers the bottom drawer. The overlap of the downward extension of the end walls effects a tight end closure for the drawers since the end walls both front and rear meet and abut edge to edge. The overlap of the top edges of the side walls and the runners of the drawers above effects a tight side seal of the middle and lower drawers.

Thus there is provided a simple and sturdy construction in which the drawers support and guide and seal

each other without any intermediate covers or closure strips.

The construction above described and shown in the drawings is intended to be illustrative merely of one embodiment of the invention. It is obvious that the particular construction may be modified without departing from the spirit and scope of the invention as defined in the following claims.

What is claimed is:

1. A merchandise display device comprising a rectangular open frame with upright side members and top and bottom members spanning the side members, and a plurality of similar superposed drawers of transparent material supported and guided in the frame, the inner faces of the side members of the frame having longitudinal guide grooves therein, and each drawer having an open top and having side walls and a bottom wall substantially longer than the longitudinal dimension of the frame and having front and rear end walls of substantially the height of the side walls and offset downwardly with respect to the side walls, thereby having their top and bottom edges below the top and bottom edges of the side walls, two longitudinal runners on the under side of the bottom wall, one near each edge and spaced therefrom by substantially the thickness of the side wall and having a height substantially equal to the said downward offset of the front and rear walls, and a longitudinal rib on the outer face of each side wall fitting and guided in one of the grooves, the grooves being so spaced that each drawer above the bottom drawer has its runners overlapping the top edges of the side walls of the drawer immediately below it and the corresponding end walls of adjacent drawers being in the same vertical plane with their adjacent upper and lower edges substantially in abutting relation when the drawers are closed.

2. A merchandise display device as defined in claim 1 in which the grooves are closed at their rear ends and the ribs extend from the front ends and terminate short of the rear ends of the drawers and engage the closed ends of the slots as stops in the closed position of the drawers, the stop ends of the ribs being similarly disposed on the drawers, whereby the front and rear walls are in the same respective planes when the drawers are closed.

3. A merchandise display device as defined in claim 1 together with a transparent cover plate carried by the under side of the top frame member fitting between the two side walls of the top drawer and of the length of the drawer.

4. A merchandise display device as defined in claim 1 in which the end walls of the drawers are notched at each of their lower corners to admit the side walls of the drawer immediately below as the drawers are opened.

5. A merchandise display device as defined in claim 1 in which the front walls of the drawers laterally overlap the side walls by the width of the ribs.

6. A merchandise display device as defined in claim 1 in which the top face of the ribs is in the plane of the top edge of the front and rear walls of the drawers.
